PISTON EXPANDER

Harold P. Phillips, Hastings, Mich., assignor to
Hastings Manufacturing Company, Hastings,
Mich., a corporation of Michigan

Application May 31, 1940, Serial No. 338,162

9 Claims. (Cl. 309—12)

This invention relates to improvements in piston expanders.

The main objects of this invention are:

First, to provide an improved expander for the skirts of internal combustion engine pistons and the like whereby objectional localization of the expansive action on the skirt is prevented.

Second, to provide an expander of the type described which is effectively locked interiorly of the piston skirt against movement resulting from inertia forces existent at high operating speeds.

Third, to provide a simple inexpensive expander of the type described in which objectionable wear on the piston skirt is eliminated and which is readily assembled in the piston.

Fourth, to provide an expander for the skirts of pistons of the unsplit type which is easily and quickly installed and at the same time securely retained.

Objects relating to details and economies of the invention will appear from the description to follow. The invention is defined in the claims.

A structure embodying the features of the invention is illustrated in the accompanying drawing, wherein:

Fig. 1 is a view in vertical section on line 1—1 of Fig. 2 illustrating an internal combustion engine piston with the expander of my invention operatively assembled therewith.

Fig. 2 is a view partially in vertical section on line 2—2 of Fig. 1, the view being taken at right angles to that figure.

Fig. 3 is a perspective view illustrating the mounting and thrust distributing element of the expander of the invention.

Fig. 4 is a perspective view illustrating the spring expander element of the invention.

Fig. 5 is a bottom plan view further illustrating the construction and arrangement of the parts in the embodiment of Figs. 1 to 4.

Fig. 6 is a fragmentary view in section generally similar to that of Fig. 2, illustrating a somewhat modified assembly embodying my invention.

In the design of expanders for piston skirts adapted to take up for piston wear and collapse, serious trouble has been experienced in the difficulty of providing locking means successfully effective to lock the expander in the piston skirt so as to resist a tendency to displace the same at high piston speeds. Since the usual piston skirt, particularly in the case of steel pistons, is very flexible, a mere frictional engagement is not always successful to retain an expander in

place, hence it is desirable to provide some positively acting device for this purpose.

Moreover, a further objection to certain expanders now on the market and designed to exert force on the piston skirt at right angles to the wrist pin so as to render the piston slightly elliptical is the extremely localized action of the expander. This results in excessive early wear of the piston skirt in certain small areas or points thereof.

It is therefore the general purpose of the present invention to provide a piston expander of a simplified nature, which is positively and effectively locked in operative position within the skirt and which, moreover, has means for distributing its expansive thrust. Still further, in the present device provision is made for adjusting the force exerted by the expander as may be required in different installations.

Referring to the drawing, the reference numeral 1 indicates an internal combustion engine piston of an extensively used type. Though particularly designed for application to a piston of steel having a thin walled skirt, my invention is not limited in this particular. The piston is provided with conventional wrist pin bosses 2 in the skirt 3 thereof. In the embodiment of Figs. 1 to 5, it will be observed that these bosses are ribbed or filleted at 4 for strength and

rigidity. The expander of my invention is of two-part construction including a mounting and force distributing member generally indicated 5 and illustrated in Fig. 3, which is in the form of a sheet metal stamping. This member has a pair of spaced plate-like vertical side members 6 each provided with a rounded seat 7 adapted to rest on the wrist pin bosses 2 or, alternatively, on the wrist pin immediately adjacent the bosses. Intermediate the parts 6, the member 5 is provided with angularly arranged arms 8 each terminating in a segmental thrust applying and distributing surface or pad 9 engageable with the interior of the piston skirt 3 in the manner clearly illustrated in Fig. 1. The sides of the areas 9 laterally of the arms 8 are bent double at 10 and each provided with pairs of notches 11 for the reception of the expander member or ring 12 illustrated in Fig. 4.

The expander ring 12 is of a high grade spring steel stock split at 13 and provided with axial offsets 14 to accommodate the stiffening webs 4 on the wrist pin bosses, it being understood that the forces distributing thrust members 9 are, in operative position, arranged at 90° to

these bosses and the offsets 14 in angular register with the bosses. In the event the webs 4 are not present, as in the type of piston illustrated in Fig. 5, these webs are eliminated since they are not of the essence of the present invention. It should be noted, however, that the expander ring 12 is in either embodiment disposed beneath the bosses so as to resist axial movement of the expander assembly under the forces of inertia arising upon reversal of the direction of piston movement.

The ring 12 may be selectively disposed in either vertical set of notches 11, depending upon the thrust desired or necessary to effect the proper distortion of the piston skirt and in this manner my device provides a range of adjustment of the force exerted thereby.

The sheet metal stirrup or saddle member 5 does not have any particular spring action or tension in itself, being, as stated, mainly a mounting element performing mainly the functions of mounting the assembly and, by means of the enlarged pads or thrust members 9, distributing the radial thrust so as to eliminate objectionable localizing of the thrust and consequent localized wear on the piston skirt. It will be noted that in Fig. 6 I have indicated an engagement of the plate-like side members 6 of this saddle member with the wrist pin 15 immediately adjacent bosses 2 rather than with the bosses themselves. In this particular, a mere matter of choice is involved.

As stated, the outline of expander member 12 is capable of considerable variation so long as it serves effectively as an expanding means and, in addition, restrains axial movement of the assembly in one direction relative to the piston. It may be desired to clear any projections on the piston skirt other than the ribs 4 and, if desired, could be made more elliptical or rectangular to this end. In fact, by alterations in design, which will occur to those skilled in the art, the expander ring may be bent so as to pass over the ends of the wrist pin bosses.

The foregoing expander assembly has a very effective spring loading action without the excessive localization of thrust and wear which has commonly characterized hitherto known skirt expanders of the so-called "bull ring" type. The tension thereof can be altered either by controlling the design of the expander ring or its relative positioning with reference to its mounting member 5 therefor. The parts are effectively locked from movement, which is of considerable importance in the case of a steel ring having substantial flexibility and in which the frictional engagement of the expander is insufficient to prevent shifting.

I have illustrated and described my improvements in an embodiment which is very practical. I have not attempted to illustrate and describe other embodiments or adaptations as it is believed this disclosure will enable those skilled in the art to embody or adapt my improvements as may be desired.

Having thus described my invention, what I claim as new and desire to secure by Letters Patent, is:

1. An expander assembly for piston skirts, comprising a sheet metal member having integral curved surfaces engageable with the upper half of the connecting rod attaching means of the piston and provided with integral radially directed portions terminating in rounded pads of substantial area concentric with and engageable with the

skirt approximately 90° from said means, and an annular split spring steel ring engageable with said pads to resiliently urge the latter outwardly, said pads having means for adjustably positioning the ring relative thereto and to prevent axial displacement thereof, and said ring being disposed beneath said connecting rod attaching means and engaging the lower half thereof for coaction with the aforesaid curved surfaces to prevent axial movement of the assembly relative to the piston, said pads distributing the thrust of said ring to prevent localized frictional wearing of the skirt.

2. An expander assembly for piston skirts, comprising a sheet metal member having integral curved surfaces engageable with the upper half of the connecting rod attaching means of the piston and provided with integral radially directed portions terminating in rounded pads of substantial area concentric with and engageable with the skirt approximately 90° from said means, and spring means engageable with said pads to resiliently urge the latter outwardly, said pads having means for adjustably positioning the ring relative thereto and to prevent axial displacement thereof, and said spring means engaging the lower half of the aforesaid connecting rod attaching means to prevent axial movement of the assembly relative to the piston, said pads distributing the thrust of said ring to prevent localized frictional wearing of the skirt.

3. An expander assembly for piston skirts, comprising a non-expansive sheet metal member engageable with the piston above the wrist pin bosses of the piston to prevent axial movement of the member, said member being provided with radially directed portions terminating in rounded pads of substantial area engageable with the skirt intermediate the bosses, and an annular split steel spring engageable with said pads to resiliently urge the latter outwardly, said pads having means for adjustably positioning the spring relative thereto, said spring engaging the piston beneath the wrist pin bosses and coacting with said member to prevent movement of the assembly relative to the bosses, said pads distributing the thrust of said spring to prevent localized wearing of the skirt.

4. An expander assembly for piston skirts, comprising a non-expansive member engageable with the piston on one side of the wrist pin bosses of the piston to prevent axial movement of the member, said member being provided with radially directed portions carrying rounded pads of substantial area engageable with the skirt intermediate the bosses, and an annular split steel spring engageable with said pads to resiliently urge the latter outwardly, said spring engaging the other side of said bosses coacting with said member to prevent movement of the assembly relative to the bosses, said pads distributing the thrust of said spring to prevent localized wearing of the skirt.

5. An expander assembly for expanding a piston, comprising a sheet metal member having enlarged thrust members engageable with the skirt at right angles to the wrist pin bosses therein, and an expansible removable split expander ring positively engaged with said member and contacting said pads to resiliently urge the same outwardly, said member and ring having portions engageable with the bosses on opposite axial sides thereof to prevent axial movement of the assembly relative to the piston, said thrust mem-

bers distributing the thrust of said ring to prevent localized skirt wear.

6. An expander assembly for expanding a piston skirt, comprising a non-expansible saddle member having thrust members engageable with the skirt intermediate the wrist pin bosses therein, and a split expander spring engageable with said thrust members to resiliently urge the same outwardly, said saddle member and spring having portions respectively engageable with the bosses or with the wrist pin in the bosses on opposite axial sides thereof to prevent axial movement of the assembly relative to the piston, said thrust members distributing the thrust of said ring to prevent localized skirt wear.

7. In a piston expander, the combination of a saddle member provided with spaced downwardly facing curved seats engageable with the upper surfaces of the connecting rod attaching means of a piston and provided with depending opposed arms terminating in segmental thrust members of substantial area engageable with the skirt of a piston at approximately 90° angle from the axis of the piston pin thereof, said thrust members having reversely bent vertical edges providing inwardly projecting flanges, said flanges having vertically spaced notches therein, and an annular split expander ring selectively engageable with said notches of said thrust members with the expander ring disposed beneath said connecting rod attaching means and engaging the lower surface of the same for coaction with said saddle member in preventing axial movement of the assembly when arranged within a piston, said expander having reinforcing rib receiving offsets therein.

8. In a piston expander, the combination of a

saddle member provided with spaced downwardly facing curved seats engageable with the upper surfaces of the connecting rod attaching means of a piston and provided with depending opposed arms terminating in segmental thrust members of substantial area engageable with the skirt of a piston at approximately 90° angle from the axis of the piston pin thereof, said thrust members having inwardly projecting flanges, said flanges having vertically spaced notches therein, and an annular split expander ring selectively engageable with said notches of said thrust members with the expander ring disposed beneath said connecting rod attaching means and engaging the lower surface of the same for coaction with said saddle member in preventing axial movement of the assembly when arranged within a piston.

9. In a piston expander, the combination of a saddle member provided with spaced downwardly facing curved seats engageable with the upper surface of the connecting rod attaching means of a piston and provided with depending opposed arms terminating in thrust members engageable with the skirt of a piston, said thrust members having notched inwardly projecting flanges, and an annular split expander ring engageable with said notches of said thrust members with the expander ring disposed beneath said connecting rod attaching means and engaging the lower surface of the same for coaction with said saddle member in preventing axial movement of the assembly when arranged within a piston.
